UNITED STATES PATENT OFFICE.

MOSES C. NIXON, OF CHICAGO, ILLINOIS.

BED OR ATTACHMENT THEREFOR.

Application filed September 2, 1922. Serial No. 585,939.

My invention relates to beds, the object being to provide means whereby the posture of the occupant of the bed may be changed without undue strain or annoyance; and consists, preferably, in the construction hereinafter described, which may be varied without departing from the spirit of my invention.

In the drawings, Figure 1 is a plan view 10 of a bed with my improvements attached, with lengthwise central portion broken out to reduce the width of the drawing; Fig. 2 is a side elevational view of Fig. 1; Fig. 3 is a central part of Fig. 1 on an enlarged 15 scale to better illustrate the operating mechanism; Fig. 4 is an enlarged end view on line 4-4 of Fig. 2, showing the operating mechanism at one side of the bed, the side rail, casting of supporting frame and the head 20 section being in section; Fig. 5 is a view of Fig. 6 and of the joint between the knee and foot sections from the underside, in which the brace is shown partly in dotted line to avoid obscuring other parts; Fig. 6 25 is a side view of a transverse segment for closing the openings between extending parts and to furnish anchorage for the fabric; Fig. 7 is a top view showing a modification in which a cup is substituted for the 30 segment shown in Figs. 5 and 6; Fig. 8 is an end view of modification of means for connecting and disconnecting the clutch; Fig. 9 is a side view from the left of Fig. 8, and Fig. 10 is an end view showing a side 35 rail in section with the supporting section or bracket and clamp-strap in place.

In the drawings, similar numerals of reference indicate corresponding parts in the different views, and, referring to the same, 40 1 and 2 denote the head and foot respectively and 3 the side rails of a bed, thereby furnishing a supporting frame to which my improvements may be attached. Secured to these rails are supporting brackets 4, which 45 in the present case forms the central section or seat member of the jointed frame. These brackets are formed with a base 5 adapted to rest upon the top of the rails (see Fig. 10). The central part of the brackets extend 50 upward, flush with the outerside of the rails, and at the proper height turn inward to form anchorage 6 or central section of a joint to which the fabric that supports the mattress may be attached. The brackets 55 turn over the inner-side and adapted to rest against the vertical angle of the rails, there-

by forming a brace 7 against the strain incident to the weight upon the fabric. Beneath the rails and extending downward from this brace are hangers 8 adapted to support the operating mechanism, and extending upward above anchorage 6 are ears or parts 9 adapted to form a part of hinges 10, the object of which will appear later. These brackets may be firmly, but preferably 60 detachably secured to the rails, as by clamp-straps 11 formed of flat steel with a hole at each end, near which they are bent to right angles. Midway the brackets and near their base are openings 12 through which clamp-straps pass, with others, toward each end, all of which are bent around the base of the brackets and the rails and drawn, as by bolts 13, thereby securing the former to the latter, without perforating the same. 65 And, while these brackets are shown and described as integral stampings, it is manifest that they could be made of separate parts and firmly secured together in any suitable manner. 70

Pivotal secured to the central section or seat member, as by hinges 10, are the body and thigh supporting sections or members 14 and 15 respectively, and to the latter is pivotally attached a leg section or member 16, 75 thereby forming a jointed frame to which the fabric 17 (only small section shown) that supports the mattress is attached, as by helicals 18. Since this jointed frame, of which the brackets and central section is a part, furnishes support for the fabric and the operating mechanism, it is apparent that a different base for the brackets could be used, to which the central section, and the supports for the operating mechanism could be firmly 80 secured in any suitable manner, and the base extended as a supporting frame, thereby 85 forming a self-contained independent structure. 90

The upwardly extending parts 9 and parts 19 with spacers 20 between, secured to the brackets by rivets or other suitable means, forms one part of the hinges, and parts 21 secured to the body and thigh members form the other part. If the pivot centers are low 95 down with sufficient clearance to permit the pivoted members being raised to meet requirements, it would leave an open space between the anchorage 6 and extending parts 22 permitting the bedding to sag into it, and 100 when the members are raised damage is liable to occur. To avoid this contingency 105

5 pivot centers 25 are raised to near the level of said anchorage, which is made possible by the upwardly extending ears 9, thereby permitting the anchorage and extending angles to be brought closer together, and the intervening space may be filled by an elongated rivet head 24. The openings that would occur below the pivots when the movable members are raised may be avoided by 10 extending the lower portion 25 of parts 21, so as to continually lap with the upright portion of the brackets.

15 The pivoted connection between the thigh and leg members are preferably made by shearing off the extending angles or parts 22 of both members and pivotally securing them together, as by rivets 26. This construction leaves an open space between the extending parts and when the pivoted ends 20 are raised permits the bedding to sag into it, and when lowered damage is liable to occur. To prevent this, parts 27 are provided (see Figs. 5 and 6), which are formed with a transverse segment of a cylindrical 25 form 28 at one end and notches 29, 29^a and 29^b at the other. These parts may be firmly secured to either member but in the present case are secured to the thigh member and so positioned that the extending angles of 30 the leg member will swing close to them while being raised and lowered, thereby closing the openings and preventing the bedding from sagging into them. These parts could also be made to fill another 35 important place by attaching the fabric to them through holes 30, thereby preventing the sagging that would follow the bending of these joints if the fabric is attached to the extending angles further from them.

40 A modification of these segments are cups 28' (see Fig. 7) adapted to be secured in place, as by rivets 26', that form pivot connections between the thigh and leg members. The size of the cups should be such that 45 the extending angles would swing close to them thereby closing and preventing the bedding from sagging into the openings, the fabric being attached through holes 30' as in the other case. It is understood, of course, that either of the devices described may be used to fill the openings at the different pivoted joints, and are not limited to the locations as herein shown.

50 If the leg member is permitted to drag 55 while its connecting end with the thigh member is being raised until an acute angle is reached, the tendency would be to eventually damage the mattress and be less comfortable to the occupant of the bed. To 60 avoid this, a bar or brace 31 is provided. While they may be carried in any suitable manner by either the thigh or leg member, in the present case they are pivotally attached to the latter, as by rivets 32, with 65 ends 33 extending beyond the pivot connec-

tions of two members, the ends 34 being adapted to contact with the frame to which they are secured, holding the braces in position to guide ends 33 into stops or notches 29, thus automatically forming braces that 70 will lift the free end of the leg member by further movement of the thigh member. Then, if desired to further raise the free end of the leg member it may be done by lifting it and placing ends of the braces in stops or 75 notches 29^a, or 29^b as preferred. From the central part of these braces to their free ends they are reduced to avoid interfering with the other parts when jointed frame is 80 lowered to a flat or normal position.

To prevent the sides of the jointed frame being drawn toward each other by the weight upon the fabric, a spreader 35 is provided, which is firmly secured in any suitable manner to opposite sides of the frame, the number used being governed by requirements. This spreader is offset near its ends far enough to drop below the fabric to prevent the latter resting upon it, thus avoiding rigid resistance to the same when weighted by the occupant of the bed.

Pivots supported in bearings 36 are supporting frames 37, each of which carry an operating mechanism, said frames being composed of castings 38 secured to connecting rods 39. These castings are provided with sockets and are slotted between ears 40 to permit contraction. Into these sockets the ends of connecting rods are placed, permitting adjustment, after which they may be firmly clamped, as by bolts 41. The length of the rods and frames depending upon the width of the bed on which they are used, so that the pivot ends may rest in 100 said bearings. To prevent frames 37 from slipping from bearings screws 42 are tapped into the pivot ends (see Fig. 4) and on said screws are washers 43 with a larger diameter than that of the openings of the bearings, which will prevent said pivots from slipping therefrom. The castings are formed with 105 openings 44, in which are gears 45, the hubs of which are bored and threaded. Said castings are also provided with transverse round holes, through which threaded rods 46 pass and around them said gears revolve.

110 Castings 38 also furnish support and bearings for driving shafts 47, which are journaled therein and to them are secured gears 48 that mate with and drive gears 45, which 115 revolve around the threaded rods, the latter being bent near their upper end to right angles and reduced with shoulders 49 thereon and projecting through holes in brackets 50 (see Fig. 4) secured to the underside of 120 the body and thigh members of the jointed frame, by which the pivoted members are raised and lowered in adjusting their positions. These ends are further reduced and 125 threaded with a nut 51 thereon with sufficient 130

play between them and the shoulders to permit adjustment to compensate for variation of construction or width of beds. The operation of the mechanism referred to is described in previous applications that resulted in Patents Nos. 1,348,820 and 1,398,271.

The construction described provides for operating the body and thigh members separately, but it is desired to provide mechanism whereby the pivoted members of the jointed frame may be operated simultaneously or singly as preferred. To accomplish this, sprocket wheel 52 is mounted upon one of the driving shafts and secured thereto, as by pin 53, and loosely mounted upon the other driving shaft is sprocket wheel 54, which is operatively connected therewith, as by clutch 55, the driving half being firmly secured to said shaft, as by pin 56. The wheel and its connecting half of the clutch being slidably mounted upon the shaft, the clutch may be operated by lever 57, which is pivotally secured to ear 58 that extends from one of the castings 38^a, as by bolt 59, and is connected with the clutch, as by pins 60, that extend from above and below into groove 61 in the sprocket wheel hub. At the opposite side of the bed is a lever 62 pivotally secured to a similar ear 58' that extends from the other casting 38^a and is operatively connected with the lever 57, as by rods 63, thereby providing means for connecting and disconnecting the clutch from either side of the bed. The two sprocket wheels are operatively connected, as by chain 64, and when the clutch is connected the pivoted members of the jointed frame may be simultaneously operated, as by crank 65, which may be applied at either end of shafts 47, made operative, as by pins 65', and by disconnecting the clutch, the operating mechanism and the pivoted members of the jointed frame with which they are connected may be operated singly.

The term "normal position" as used in some of the claims is intended to mean the position of the pivoted members of the jointed frame when they are in a single plane or flat position.

A modification of means for connecting and disconnecting the clutch is shown in Figs. 8 and 9, in which castings 38', connecting rod 39' and driving shaft 47' are similar to those described as 38, 39 and 47, except that the castings are provided with additional bearings 67, and revolvably mounted therein is a shaft 68 on which is firmly secured a worm 69, as by pin 70. The sprocket wheel 54' and clutch 55' are similar to those described as 54 and 55, except that the hub of the sprocket wheel is provided with a rim 71, instead of the groove 61, that operates in conjunction with the worm, and by turning shaft 68 the worm causes the

sprocket wheel and its connecting half of the clutch to slide upon the shaft thereby connecting or disconnecting the latter. This shaft being the same size and arranged for the same operating connection as the driving shafts 47 it may be operated by the same crank 65, which may be applied at either end thereby connecting or disconnecting the clutch from either side of the bed.

If desired to raise either the body and thigh members faster than the other, it is evident that may be accomplished by having one of the sprocket wheels larger than the other and the movement of the pivoted sections will be governed accordingly.

While the preferred embodiment of my invention has been described herein I do not wish to be limited to the details of construction shown as it is apparent that changes may readily be made without departing from the spirit of my invention, and having described one form of construction I claim as new and desire to secure by Letters Patent the following:

1. In a structure of the class described, the combination of a member pivotally supported at one end, another member pivotally attached to the free end of the supported member, and means pivotally attached to and normally extending beyond the end of one of said members and adapted to automatically form a brace as the pivotally connected ends of said members are elevated whereby the free end of the attached member may be raised by the movement of the supported member.

2. In a structure of the class described, the combination of a jointed frame having openings between extending parts at pivot connections, and means adapted to prevent bedding from sagging into said openings and furnish anchorage for a mattress supporting fabric.

3. In a structure of the class described, the combination of a jointed frame embodying a central section and members pivotally secured thereto, gears at each side of said structure, operative connections between the pivoted members and said gears, and means adapted to rotate said gears around said connections whereby the position of said members may be adjusted either singly or simultaneously.

4. In a structure of the class described, the combination of a support a member pivotally supported thereby at one end, another member pivotally attached to the free end of the pivotally supported member, and a brace between said members so arranged that the free end of the pivotally attached member may be raised by a rising movement of the pivotally supported member, said brace being releasable by contact of the pivotally attached member with the support upon lowering said members to normal position.

5. In a structure of the class described, the combination of a support, a member pivotally supported thereby at one end, another member pivotally attached to the free end of the pivotally supported member, and a brace between said members so arranged that the free end of the attached member may be raised by a rising movement of the pivotally supported member, said brace being automatically releasable as said members are lowered to normal position and so constructed as to permit the latter to be lowered to a flat position.

10 6. In a structure of the class described, the combination of a member pivotally supported at one end, another member pivotally attached to the free end of the pivotally supported member, a member pivotally secured to one of said members and a co-acting member carried by the other pivoted member, and means adapted to guide one end of the secured member into contact with its coacting member thereby forming a brace that is brought into action by elevating the pivotally supported member through which the free end of the attached member may be raised by a rising movement of the pivotally supported member.

15 7. In a structure of the class described, the combination of a support a member pivotally supported thereby at one end and arranged so the free end thereof may be raised and lowered to different positions, another member pivotally attached to the free end of the pivotally supported member, and a brace between said members so arranged that the attached member may be supported in a raised position by the pivotally supported member, said brace being adapted to release by engagement of the attached member with said support as said members are being lowered to normal position.

20 8. In a structure of the class described, the combination of a support a member pivotally supported thereby at one end and arranged so the other end thereof may be raised and lowered to different positions, another member pivotally attached to the free end of the pivotally supported member, and means adapted to form a brace between said members whereby the attached member may be supported by the pivotally supported member in a raised position, said brace automatically releasing and avoiding interference with said members as the latter are lowered into normal position.

25 9. In a structure of the class described, the combination of a member pivotally supported at one end and arranged so the other end thereof may be raised and lowered to different positions, another member pivotally attached to the free end of the pivotally supported member, a member pivotally secured to one of said pivoted members and a coacting member carried by the other piv-

30 oted member, and means adapted to guide a portion of the pivotally secured member into contact with its co-acting member thereby forming a brace which is brought into action by elevating the pivotally supported member and adapted to support said attached member when its free end is in a raised position.

35 10. In a structure of the class described, the combination of a support a member pivotally supported thereby at one end, operating means adapted to raise and lower the free end of said member to different positions, another member pivotally attached to the free end of the pivotally supported member, a member pivotally secured to one of said pivoted members and a co-acting part carried by the other pivoted member thereby forming a brace adapted to support said attached member when in raised position, said brace being adapted to release automatically as said pivoted members are lowered to normal position.

40 11. In a structure of the class described, the combination of a support, a member pivotally supported thereby at one end, operating means adapted to raise and lower the free end of said member to different positions, another member pivotally attached to the free end of the pivotally supported member, a member pivotally secured to one of said pivoted members and a co-acting member carried by the other pivoted member thereby forming a brace adapted to support said attached member when in a raised position, said brace being adapted to release automatically as said pivoted members are being lowered to normal position.

45 12. In a structure of the class described, the combination of a fabric supporting frame embodying members having co-engaging portions, means adapted to pivotally secure said portions together, the ends of said members adjacent said portions being cut out to provide for free swinging movement of said members, and means adapted to close the cut out places and to provide anchorage for the fabric at said cut out places.

50 13. In a structure of the class described, the combination of a fabric supporting frame embodying members having co-engaging portions, a pivot pin extending through said portions, the ends of said members adjacent said portions being cut out to provide for free swinging movement of said members, and means adapted to provide anchorage for the fabric at said cut out places.

55 14. In a structure of the class described, the combination of a jointed frame embodying a central seat section and members pivotally secured to the respective ends of said central seat section, means connected with said pivoted members, and means rotatable around said connected means, and driving means for said rotatable means whereby the

free end of the pivoted members may be simultaneously or independently raised or lowered to different positions.

15. In a structure of the class described, the combination of a jointed frame embodying a central seat section and members pivotally secured to said central seat section, means connected with said pivoted members, and means rotatable around said connected means and so arranged that the free end of the pivoted members may be simultaneously or independently raised or lowered to different positions.

16. In a structure of the class described, the combination of a support, a member pivotally supported thereby at one end, another member pivotally attached to the free end of the pivotally supported member, and a brace between said members so arranged that the free end of the attached member may be raised and lowered by raising and lowering the pivotally supported member, said brace being adapted to support the pivotally attached member in different positions relative to the pivotally supported member when the former is adjusted manually and being automatically releasable by the pivotally attached member engaging with said support upon lowering said members to normal position.

17. In a structure of the class described, the combination of frame members having co-engaging portions, a member extending through said portions for pivotally connecting said frame members, the ends of said frame members adjacent said pivotal connection having cut-out portions to provide for free swinging movement of the frame members, and rigid means connected to one of said members and adapted to close said cut-out places for the purpose specified.

18. In a structure of the class described, the combination of fabric supporting frame members having co-engaging portions, a member extending through said portions for pivotally connecting said frame members, the ends of said frame members adjacent said pivotal connection having cut-out portions to provide for free swinging movement of the frame members, and rigid means connected to one of said members, adapted to close said cut-out places and to provide an anchorage for the fabric at said cut-out places.

19. In a structure of the class described, the combination of frame members having co-engaging portions, a member extending through said portions for pivotally connecting said frame members, the ends of said frame members adjacent said pivotal connection having cut-out portions to provide for free swinging movement of the frame members, and rigid means connected to one of said members and having a convexed portion adapted to close said cut-out places.

20. In a structure of the class described, the combination of fabric supporting frame members having co-engaging portions, a member extending through said portions for pivotally connecting said frame members, the ends of said frame members adjacent said pivotal connection having cut-out portions to provide for free swinging movement of the frame members, and convexed portions adapted to close said cut-out places and to provide an anchorage for the fabric at such cut-out places.

21. In a structure of the class described, the combination of frame members having co-engaging portions, a member extending through said portions for pivotally connecting said frame members, the ends of said frame members adjacent said pivotal connection having cut-out portions to provide for free swinging movement of the frame members, and a member connected to one of said members and having a convexed portion with which the adjacent end of the other frame member co-operates thereby substantially closing said cut-out places.

22. In a structure of the class described, the combination of fabric supporting frame members having co-engaging portions, a member extending through said portions for pivotally connecting said frame members, the ends of said frame members adjacent said pivotal connection having cut-out portions to provide for free swinging movement of the frame members, and a member connected to one of said frame members and having a convexed portion with which the adjacent end of the other frame member co-operates, thereby substantially closing said cut-out places, and providing an anchorage for the fabric at said cut-out places.

23. In a structure of the class described, the combination of a central section, members each pivotally secured at one end to the respective ends of the central section, elements pivotally secured to said members and supported for reciprocating movement, operating means for imparting such movement to said elements, and means whereby the operating means may be caused to drive said elements simultaneously or independently.

24. In a structure of the class described, the combination of a central section members each pivotally secured at one end to the respective ends of the central section, elements pivotally secured to said members intermediate of their ends and supported for reciprocating movement, rotatable means for imparting such movement to said elements, and means whereby the rotatable means may be caused to drive said elements simultaneously or independently.

25. In a structure of the class described, the combination of a central section, members each pivotally secured at one end to the respective ends of the central section, ele-

ments pivotally secured to said members, rotatable means adapted to impart a reciprocating movement to said elements, and means for driving said rotatable means whereby the free end of said members may be raised or lowered simultaneously or each independently.

26. In a structure of the class described, the combination of a central section, members each pivotally secured at one end to the respective ends of the central section, elements pivotally secured to said members intermediate of their ends, operating means adapted to impart a reciprocating movement to said elements, and means for driving said operating means whereby the free end of said members may be raised and lowered simultaneously or each independently.

27. In a structure of the class described, the combination of a central section, members each pivotally secured at one end to the respective ends of the central section, elements pivotally secured to said members and supported for reciprocating movement, operating means for imparting such movement to said elements, pivoted support for said operating means, and means for driving said operating means whereby the free end of said members may be raised and lowered simultaneously or each independently.

28. In a structure of the class described, the combination of a central section, members each pivotally secured at one end to the respective ends of the central section, rotatable means with operative connection with said members, pivoted support for said rotatable means, and means for driving said rotatable means whereby the free end of said members may be raised and lowered simultaneously or each independently.

29. In a structure of the class described, the combination of a central section, members each pivotally secured at one end to the respective ends of the central section, elements pivotally secured to said members, operating means adapted to impart a reciprocating movement to said elements, and means for driving said operating means whereby the position of said members may be adjusted simultaneously or each independently.

30. In a structure of the class described,

the combination of frame members having co-engaging portions, a member extending through said portions for pivotally connecting said frame members, one of said frame members having a cut out portion adjacent said pivotal connection to provide for free swinging movement of the other frame member, and an extending portion carried by one of the members and adapted to prevent bedding from sagging into the opening caused by said cut out portion.

31. In a structure of the class described, the combination of frame members having co-engaging portions, a member extending through said portions for pivotally connecting said frame members, a portion of said frame members cut away adjacent said pivotal connection to provide for free swinging movement of said frame members, and extending means carried by one of said members and adapted to approximately close the opening caused by said cut out portion.

32. In a structure of the class described, the combination of a member pivotally supported at one end and arranged so the other end thereof may be raised and lowered to different positions, another member pivotally attached to the free end of the pivotally supported member, elements carried by one of said pivoted members and coacting means carried by the other pivoted member, one end of each of said elements being so arranged as to guide the other end thereof into contact with the co-acting means thereby forming a brace which is brought into action by elevating the pivotally supported member and is adapted to support said attached member as its free end is elevated.

33. In a structure of the class described, the combination of frame members having co-engaging portions, a pivot connection extending through said portions for pivotally connecting said frame members, the ends of said frame members adjacent said pivotal connection having cut-away portions to provide for free swinging movement of the frame members, and means extending from the pivot connection adapted to substantially close the opening caused by said cut-away portions.

MOSES C. NIXON.
